UNITED STATES PATENT OFFICE

2,152,735

SOLE FITTING MACHINE

Trygve Gulbrandsen, Beverly, Mass., assignor to
 United Shoe Machinery Corporation, Paterson,
 N. J., a corporation of New Jersey

Application January 10, 1938, Serial No. 184,179

5 Claims. (Cl. 12—27)

This invention relates to sole fitting machines and is herein illustrated and described as embodied in a channeling machine of the type disclosed in United States Letters Patent No. 2,015,064, granted September 24, 1935, upon the application of Frederic E. Bertrand. The machine disclosed in that patent is provided with a pair of channeling knives which are normally held in operating position by springs. The work is supported upon a work table and a treadle-operated mechanism is provided for raising the knives out of operating position and also for lowering the work table to enable the operator to insert and replace a sole.

15 It is an object of the present invention to provide improved means for moving the operating knife of a sole-fitting machine out of its normal or operating position. In accordance with a feature of the invention a positive connection is 20 provided between a treadle and the knife for moving the knife out of operating position upon movement of the treadle and mechanism is also provided for disengaging the positive connection upon further movement of the treadle, thereby 25 enabling resilient means to return the knife to operating position. In the illustrated construction means is also provided for delaying the return of the knife to operating position during a portion of the further movement of the treadle 30 to afford the operator time to remove a work-piece.

The invention further resides in features of construction and combinations and arrangements of parts hereinafter described and claimed, the 35 advantages of which will be apparent to those skilled in the art from the following description.

The invention will be described with reference to the accompanying drawing, in which

Fig. 1 is a view in side elevation of a portion 40 of a channeling machine provided with the improved knife-lifting mechanism;

Fig. 2 is a sectional view taken on the line II—II of Fig. 1;

Fig. 3 is a sectional view in front elevation showing a channeling knife and its supporting means 45 in relation to a work table.

As has already been mentioned, the improvements about to be described are illustrated as embodied in a machine of the type disclosed in United States Letters Patent above referred to. For convenience, therefore, those portions of the machine shown herein which are identical with portions disclosed in the patent will be identified herein by the same reference characters as in the 50 patent.

The supporting structure of the machine comprises a frame 76 upon which is mounted a head 74. Referring to Fig. 3, a channeling knife 42 is carried by a slide 186 which is guided for vertical movement in a slideway formed in a carrier 62 which, in turn, is supported for oscillatory movement upon a pin 156 journaled in a bearing 160 formed in the head 74. The slide 186 is urged downwardly toward a work-supporting table 40 by a spring 224 housed within a bore in the upper portion of the slide. The upper end of the spring 224 bears against a plunger 226 which engages a screw 228 threaded through a bracket 230 secured upon the carrier 62. The lower end of the spring 224 bears against the lower end of the 10 above-mentioned bore and thus urges the slide downwardly to a stop position determined by the engagement of a lug 232 (Fig. 1) and a shoulder formed on the carrier 62. The stop lug 232 is formed at the extremity of a cross-bar 236 secured to the slide 186. The knife 42 forms the inner lip of a double lipped insole. In Fig. 3 is shown also an edge knife 44 for forming the outer lip of such an insole.

The knife 42 is raised from its operating position by an arm 580 secured upon a rockshaft 584 which is journaled in suitable bearings formed in the head 74. The rockshaft 584 is operated, through mechanism presently to be described, by a treadle 490 fulcrumed upon a shaft 492 which is 20 journaled in the base of the machine. An arm 604 secured upon the shaft 492 is pivotally connected to the lower end of a rod 602. A spring 603 surrounding the rod 602 urges the rod upwardly and tends to hold the treadle 490 in normal raised position. All the parts so far described are identical with corresponding parts disclosed in the above-mentioned Letters Patent No. 2,015,064 and are identified by the same reference characters.

The upper end of the rod 602 is pivotally connected to an arm 700 having a hub 702 by which the arm 700 is fulcrumed upon a stud 704 secured in the head 74. Integral with the arm 700 and extending in an opposite direction from the hub 45 702 is an arm 706. A third arm 708 integral with the arms 700 and 706 extends upwardly from the hub 702. The arms 700, 706 and 708, together with the hub 702, thus constitute a three-armed lever fulcrumed upon the stud 704. Mounted for 50 heightwise sliding movement in a guideway 707 formed in the arm 708 is a block 710. A plate 712 secured to the arm 708 by a pair of screws 714 retains the block 710 in its slideway. A tension spring 716 secured at its upper end to the arm 708 55

and at its lower end to the block 710 urges the block upwardly. A narrow groove 711 formed in the arm 708 accommodates the spring 716. Secured in the block 710 is a pin 718 upon which is mounted a roll 720. The block 710 is retracted in its guideway 707 against the force of the spring 716 by a flange 722 formed on one arm of a bell crank 724 which is journaled upon a stud 726 secured in a bracket 728 extending from the head 10 74. The other arm of the bell crank 724 is connected by a link 730 to the arm 706. In order to provide for adjustment of the bell crank 724 relatively to the arm 706 the lower end of the link 730 is pivotally mounted upon an eccentric 732 formed 15 upon a pin 734 which may be secured in any desired position of rotary adjustment in the arm 706 by a set screw 736.

Movement of the treadle 490 is communicated through the block 710 to an arm 738 secured upon 20 the rockshaft 584. Integral with the arm 738 is an extension 740 in which is formed a latching shoulder 742 engageable with a detent 744. The detent 744 is pivotally mounted upon a pin 746 secured in the head 74. A tension spring 748 25 connects the upper portion of the detent to the hub of the arm 738 and urges the detent into latching position. An abutment flange 750 formed in the plate 712 engages a screw 752 threaded through the detent 744. 30 In operating the improved mechanism the treadle 490 is depressed, causing the rod 602 to rock the three-armed lever 700, 706 and 708 in a counterclockwise direction, as viewed in Fig. 1. The upper end of the block 710 will thus rock 35 the arm 738 in a clockwise direction, causing the arm 580 to raise the knife slide 186. As the block 710 is swung to the left, as viewed in Fig. 1, it is also depressed by the bell crank 724 until it disengages the arm 738. By that time, 40 however, the detent 744 has been drawn by the spring 748 into engaging position below the latch shoulder 742. The detent 744 thus prevents return of the knife 42 to operating position until the arm 708 has been advanced far enough by 45 continued movement of the treadle for the abutment 750 to engage the screw 752 and thus move the detent out of latching position. The spring 224 is then free to return the knife 42 to operating position. The screw 752 may be adjusted to 50 engage the abutment 750 at any desired point in the travel of the treadle 490 to provide a greater or less dwell of the knife in its raised position to enable the operator to move the work-piece before the knife descends. An accurate adjustment 55 to insure disengagement of the block 710 from the arm 738 as soon as the detent 744 comes into position to engage the shoulder 742 may be effected by turning the pin 734.

The above-described mechanism offers certain 60 advantages in a machine such as that disclosed in the above-mentioned Letters Patent No. 2,015,064. In that machine, it will be recalled, the work is fed along the table 40 by a pair of four-motion feed dogs mounted in a pair of oscillating carriers, respectively. One of these carriers, already referred to by the reference numeral 62, is shown herein. The feed dogs derive their components of movement in the direction of feed from the oscillating carriers; they are 65 also raised and lowered by other means to cause them to grip the work against the table during their advancing movements and to release the work during their return movements. Each of the feed dogs carries a slashing knife in the 70 form of a cutting edge arranged to form an 75

incision in the face of the sole as the dog descends, which incisions will extend across the lips to be formed and will facilitate raising the lips at the toe end and at other curved portions of the sole. The channeling operation may be 5 stopped at any desired point by depression of the treadle 490 which results in raising the channeling knives and depressing the work table. The feed dogs are not affected by the raising of the knives and continue their up and down movements, holding the sole down relatively to the knives and thus enabling the knives to "cut out" or emerge from the surface of the sole. In order to insure against any damage which might result from the feed dogs and the slashing knives 10 striking the surface of the work table while the machine is running idly, mechanism is provided for automatically stopping the up and down movement of the feed dogs. This stopping mechanism is controlled by the knife slide 186 which 20 in turn is controlled by a presser gage riding upon the upper surface of the sole. If a sole being fed through the machine should be allowed to "run out" without the operator depressing the treadle 490, the lowering of the presser gage 25 resulting from the removal of the sole will at once cause the up and down movements of the feed dogs to cease. When the operator depresses the treadle 490 to cause the channeling knives to cut out, it is desirable to insure the stopping of 30 the up and down movements of the feed dogs before the treadle is released, inasmuch as the release of the treadle enables the work table to move upwardly into its normal position. The machine disclosed in the above-mentioned Letters Patent is accordingly provided with a mechanism for releasing the channeling knife slides before the completion of the downward movement of the treadle which at first caused them to be raised. As soon as the knife slide 186 is thus 40 returned to its lowermost position by the spring 224, the automatic mechanism above referred to will stop the up and down movements of the feed dogs. Then when the treadle 490 is released the work table 40 will be raised to normal position without the danger above mentioned. The 45 up and down movements of the feed dogs will be resumed automatically when a sole is introduced.

One advantage offered by the improved mechanism disclosed herein, when applied to a machine of the type under consideration, resides in the fact that the knife-lifting instrumentalities are positive and operate with certainty. Another advantage is that the channeling knives do not descend immediately upon reaching their uppermost positions (the height to which they may be raised and consequently the duration of their upward movements being strictly limited by practical considerations) but remain raised for an appreciable interval while the operator is depressing the treadle. This insures against any chance of the knives descending and cutting into the work before the table has been lowered out of the way, however slowly the operator may depress the treadle. In addition to these advantages, the improved mechanism disclosed herein provides for a quick raising of the channeling knives and calls for a minimum of effort on the part of the operator in depressing the treadle. 65

Having thus described my invention, what I 70 claim as new and desire to secure by Letters Patent of the United States is:

1. In a sole fitting machine, a knife for operating upon a sole, means for urging said knife toward operating position, a treadle, a positive con- 75

nection between said treadle and said knife for moving said knife out of said operating position upon movement of said treadle, and mechanism operable upon further movement of said treadle to 5 disengage said positive connection and thereby to enable said urging means to return said knife to operating position.

2. In a sole fitting machine, a knife for operating upon a sole, resilient means for normally holding said knife in operating position, a treadle, a positive connection between said treadle and said knife for moving said knife out of operating position upon movement of said treadle, said positive connection including a pair of abutting members 10 through which movement may be transmitted, and means for retracting one of said abutting members from engagement with the other abutting member laterally of their path of movement to release said knife and thereby to enable said 15 resilient means to return said knife to operating position.

3. In a sole fitting machine, a knife for operating upon a sole, a spring for normally holding said knife in operating position, a treadle, a connection between said treadle and said knife for moving said knife out of said operating position 20 upon movement of said treadle, said connection being constructed and arranged to release said knife upon further movement of the treadle, and means for delaying the return of said knife to 25 operating position under the influence of said spring during a portion of said further movement of the treadle to afford the operator time to remove a work-piece.

4. In a sole fitting machine, a knife for operating upon a sole, a spring for normally holding said knife in operating position, mechanism for moving said knife out of operating position against the force of said spring, a treadle, means connected to said treadle for operating said mechanism to move the knife out of operating position upon movement of the treadle, means for holding said knife in the inoperative position to which said knife has been moved by said treadle-operated 10 means, thereby affording the operator time to remove a work-piece, and means associated with said treadle-operated means for releasing said holding means upon continued movement of the treadle thereby to enable said spring to return the 15 knife to operating position after the work-piece has been removed.

5. In a channeling machine, a channeling knife, a spring for normally holding said knife in operating position, a rockshaft, means operated by said 20 shaft for raising said knife out of operating position against the force of said spring, an arm on said rockshaft for rocking the shaft, a treadle, mechanism operated by movement of said treadle to rock said arm to cause the knife to raise, a 25 detent for holding the arm in the position to which it has been rocked by said mechanism, and means on said mechanism for tripping said detent upon further movement of said treadle, thereby releasing said arm and enabling said spring to 30 lower the knife into operating position.

TRYGVE GULBRANDSEN.
